York, N. Y., a corporation of Delaware

Application March 29, 1933, Serial No. 663,282

3 Claims. (Cl. 179—100.3)

This invention relates to communication systems and more particularly to methods and apparatus for rapidly effecting switching operations in such systems.

An object of the invention is to provide means for gradually reducing the amplitude of signals in one communication channel and gradually increasing the amplitude of signals in another communication channel where the two channels are associated with a common output circuit.

A feature of the invention is that no sliding contacts are required for effecting the gradual changes in signal amplitude.

Another feature of the invention is that the switching operation, once initiated, proceeds automatically and with any desired rapidity.

In accordance with one embodiment of the present invention there is provided in each of the two communication channels a space discharge device to one of which is applied a potential that renders the channel in which it is included inoperative. When the latter channel is to be substituted for the operative one, a switch is manually operated which causes the disabling potential to be gradually removed from the one discharge device and simultaneously a disabling potential to be gradually applied to the discharge device in the other channel.

The invention finds a particular application in sound reproducing systems, where a plurality of separate sound records are to be associated in succession with the same reproducing channel without a noticeable break being occasioned by the transfer from one sound record to another. Such a system has been chosen for the purpose of illustrating a specific embodiment of the present invention.

Other objects and features of the invention as embodied in the preferred form will appear in the following detailed description and in the claims hereto annexed.

In the drawing.

Fig. 1 shows schematically a sound picture system in which an embodiment of the invention is incorporated; and

Figs. 2 to 4 show schematically forms of photoelectric cell circuits with which the invention may be employed.

In the sound picture system represented in Fig. 1 there is provided at each of two alternately-operated picture projection machines a photoelectric cell circuit adapted to convert the sound traces on the respective films 2 into equivalent electrical waves. These waves are transferred over a pair of conductors to remotely lo-

cated individual amplifiers V₁ and V₂, which in turn are connected to a common power amplifier V₃ operating a sound reproducer 35. The individual amplifiers are operative only when the corresponding projecting machine is in operation.

The two photoelectric cell circuits are identical. Polarizing potential for each cell 3 is supplied from a negative point on a voltage dividing resistor 43 associated with an alternating current operated power supply unit, over a conductor 13, through the lower contact of switch S₁, and resistance 9 to cathode 5 of the cell. The positive side of the polarizing circuit is completed from the grounded terminal of voltage dividing resistor 43, through tubular conductor 11, resistor 7 and resistor 6, to anode 4 of the cell. The anode of the cell is connected to the central conductor 12 of a coaxial conductor cable leading to the remotely located amplifier tube V₁, 20 to the control grid of which it is connected through a condenser 14. Cathode 5 of the cell is connected through a condenser 10 to the outer conductor 11 of the coaxial cable to which the cathode of amplifier tube V₁ is connected, and 25 to ground.

In a specific reproducing system, resistors 9, 7 and 6 were 100,000, 500 and 100,000 ohms, respectively, and the capacity of condenser 10 was two microfarads. Resistor 9 and condenser 10 30 together comprise a low frequency filter for suppressing ripples in the photoelectric cell polarizing circuit.

Terminals are associated with resistor 7 to provide for the alternative connection of a disc pick-up circuit. Ordinarily resistor 7 is short-circuited through the upper contact of switch S₁, but when the switch is operated the short circuit is removed, the photoelectric cell circuit is disabled, and signals from the disc pick-up are 40 transmitted to the amplifier.

It is to be noted that the polarizing voltage for the cell is not transmitted over the conductor pair traversed by the signals. Microphonic noise that would otherwise be produced by relative 45 movement of the conductors comprising the signal pair is thereby substantially eliminated. Whatever direct-current voltage does exist between the signaling conductors by virtue of the voltage drop in resistors 6 and 7 is small and ineffective in creating microphonic noise. The general principle to be observed in the design is that points at a high direct-current potential above ground should be connected to ground 50 55

through paths of low alternating-current impedance.

Alternative forms of photoelectric cell circuits embodying the foregoing principle are shown in Figs. 2 to 4. Fig. 2 shows a transformer-coupled circuit in which the positive terminal of the polarizing source B is connected through a half-megohm resistor 51 to the anode of the cell 3, and the grounded negative terminal is connected through the primary winding of transformer 52 to the cathode. The cathode of the cell, which is at a high positive potential above ground, is connected to ground through a large condenser 53, a path of low alternating-current impedance. In the photoelectric cell circuits represented in Figs. 3 and 4, the cell is coupled to an associated amplifier through a resistor 54, which may be of the order of a half megohm. Cathode circuit resistor 55 and grid leak 56 were 18 ohms and 10 megohms, respectively, in a particular instance. The signal output terminals of the circuits shown in Figs. 2 to 4 may be associated with the tubes V₁, V₂ through any suitable coupling circuit.

The individual amplifiers shown in Fig. 1 employ screen grid tubes V₁, V₂ of the multi-mu type. Grid polarizing potential is supplied to each from an individual potentiometer P₁, P₂ through a connection including a resistor 15, which may be of the order of 10 megohms, and a resistor 16, which may be 1 megohm. The potentiometers P₁ and P₂ comprise movable contacts 19 and 20, respectively, and respective resistors 21 and 22, which are connected in parallel between ground and a negative point on resistor 43. Volume control is secured by adjustment of the potentiometer contacts.

In the input circuits of each of the screen grid tubes V₁, V₂, there is provided between the junction of resistors 15 and 16 and the cathodes of the tubes a condenser 17, which in conjunction with resistor 16 constitutes a grid biasing filter. In accordance with the embodiment of the invention herein disclosed the same filter may be used to control the rate of fade-over from one channel to another, as will now appear.

In the grid circuits of each of the tube V₁, V₂ there is provided a double-pole, double-throw switch S₃, which in one position applies to the control grid of one tube a high negative disabling potential, and connects the control grid of the other tube to one of the potentiometer contacts 19, 20. In the alternative position of the switch, the disabling potential is transferred to the grid of the other tube and the grid of the first tube is connected to the other potentiometer contact. The left hand contacts associated with the respective blades of switch S₃ are connected together to the extreme negative terminals of the volume controlling potentiometers. When the blades of switch S₃ are thrown inward, the movable contact 20 of potentiometer P₂ is disconnected from the grid of tube V₂ and a negative voltage, which in a particular instance was approximately 75 volts, is applied to the control grid of tube V₂. With the blades of switch S₃ thrown outward, a negative voltage sufficient to render tube V₁ inoperative is connected in the control grid circuit of that tube. Because of the effect of resistor 16 and condenser 17, however, this voltage does not build up immediately but in accordance with an exponential curve. As a result of this gradual increase in negative grid bias the volume of signals in the upper chan-

nel is reduced gradually, finally becoming substantially zero.

While the upper reproducing channel is operative a disabling negative potential is normally applied to the control grid of tube V₂ in the other reproducing channel as described above. When a change-over is to be made, switch S₃ is thrown to its alternative position, the high voltage source is thereby disconnected from the grid circuit of tube V₂, and the negative potential on that grid is gradually dissipated through resistors 15 and 16, the rate of dissipation being determined by the relative magnitudes of resistor 16 and condenser 17. At some point during this gradual decrease in grid bias on tube V₂, that tube begins to become operative and the volume of signals gradually increases up to normal volume.

Thus, by operation of switch S₃, the volume of signals in one channel may be caused to gradually approach zero and at any desired point the volume of signals in the other channel to be gradually increased. The transfer from one channel to the other therefore takes place smoothly and gradually and without any manual control other than the initial operation of switch S₃.

The anodes of tubes V₁ and V₂ are connected together and through condenser 25 and inductance 26 in series to the grid of the common amplifier tube V₃. Anode current is supplied to the first two tubes through an inductance 40 connected to a point of positive potential on the voltage divider 43. Inductance 26 is so proportioned with respect to the inherent capacity between the grid of tube V₃ and ground as to be resonant at the high frequency end of the transmission band to maintain the high frequency gain. Inductance 40 and condenser 25 are so proportioned as to approximate a half section of a high-pass filter with a cut-off frequency of roughly 25 cycles per second and having an impedance approximating that of the terminating resistance connected across the grid circuit of the succeeding tube. An improvement in the gain at low frequencies is thereby obtained.

The anode of tube V₃ is connected to the power supply unit through resistance 30 and to the grid of the succeeding pentode amplifier stage V₄ through condenser 31 and inductance 33. The latter inductance functions in the same manner and for the same purpose as inductance 26 associated with tube V₃. The output signal of tube V₃ is transmitted through transformer 34 to sound reproducer 35.

While for purposes of exposition the present invention has been shown and described as embodied in a specific form and in cooperation with a sound picture reproducing system, it is capable of numerous other forms of embodiment and uses within the scope and spirit of the appended claims.

What is claimed is:

1. In a sound picture reproducing system, two sound reproducing channels, each of said channels including a photoelectric cell and a space discharge amplifying device having a control electrode that is connected to said cell through a circuit of high impedance, an output circuit common to said channels, a filter comprising resistance and capacitance in the biasing circuit connected with each of said control electrodes, and means for applying a disabling potential alternatively to said control electrodes through said respective associated filters, whereby upon the

operation of said means the amplitude of signals gradually decreases in one of said channels and gradually increases in the other without a noticeable interruption of signals in said output circuit.

5 2. A pair of individual signal transmission channels to be selectively associated in energy transfer relation with a common output circuit, a signal repeating space discharge device in each of said channels, each of said devices having an impedance controlling electrode, independent filters connected to said respective electrodes, and means for applying a disabling potential alternatively to said electrodes through said respective filters, whereby upon the operation of said means the amplitude of signals gradually decreases in one of said channels and gradually increases in the other without occasioning a noticeable interruption of signals in said output circuit.

10 15 20 3. A sound reproducing system comprising two

alternatively-operative signal channels, a common output circuit for said channels, a space discharge amplifier in each of said channels, each of said amplifiers having a control electrode, independent filters connected to said control electrodes, a source of direct voltage, volume control means for applying to said respective control electrodes through said respective filters an adjustable voltage derived from said source, and other means for applying alternatively to said electrodes through said respective filters a voltage derived from said source sufficient to block transmission through the corresponding channel, the constants of said filters being proportioned so that upon operation of said other means the gain of one of said amplifiers gradually increases and that of the other simultaneously gradually decreases.
